CLAIM

The ornamental design for a phototherapy helmet, as shown and described.

DESCRIPTION

FIG. 1 illustrates a top perspective view of a phototherapy helmet;

FIG. 2 illustrates a front view of the phototherapy helmet thereof;

FIG. 3 illustrates a back view of the phototherapy helmet thereof;

FIG. 4 illustrates a left side view of the phototherapy helmet thereof;

FIG. 5 illustrates a right side view of the phototherapy helmet thereof;

FIG. 6 illustrates a top view of the phototherapy helmet thereof;

FIG. 7 illustrates a bottom view of the phototherapy helmet thereof; and,

FIG. 8 illustrates a bottom perspective view of the phototherapy helmet thereof.

The broken lines shown in the drawings are for purpose of illustrating portions of the phototherapy helmet, which form no part of the claimed design.
